UNITED STATES PATENT OFFICE

99,657

DESIGN FOR A COMBINED SIGNAL LIGHT CASING AND LICENSE PLATE HOLDER

Joseph A. Chinsky, Baltimore, Md.

Application March 9, 1936, Serial No. 61,546

Term of patent 7 years

To all whom it may concern:

Be it known that I, Joseph A. Chinsky, a citizen of the United States, residing at Baltimore, State of Maryland, have invented a new, original, and ornamental Design for a Combined Signal Light Casing and License Plate Holder, of which the following is a specification, reference being had to the accompanying drawing, forming part thereof.

Figure 1 is a view in front elevation of a combined signal light casing and license plate holder, showing my new design.

Figure 2 is a view in side elevation thereof.

Figure 3 is a top plan view.

I claim:—

The ornamental design for a combined signal light casing and license plate holder, as shown.

JOSEPH A. CHINSKY.
